UNITED STATES PATENT OFFICE

STEPHEN STEPANIAN, OF COLUMBUS, OHIO

SAMPLE-DISPLAY HOLDER

Application filed April 24, 1926. Serial No. 104,292.

This invention relates to an improved sample holder for use in the display, for advertising or other desired purposes, of various grades of merchandise, and an outstanding object of the invention is the provision of a sample holder wherein is provided a plurality of glass jars rigidly and permanently mounted in connection with the supporting frame of the holder, and wherein the operative positions of the jars with respect to the frame are such as to admit of facility in observing or examining the contents of the jars, but wherein the removal of the jars from the frame, or of the samples from the jars, is prevented unless the entire frame structure is separated into its component parts.

Another object of the invention resides in the provision of a sample display holder especially adapted for use in promoting the display of various grades and kinds of sand, gravel and crushed stone and wherein the construction of the holder is such as to permit of the display of these materials in separate containers and wherein the construction of the containers and the frame therefor is such that it is practically impossible to remove said material, mix, lose or wrongly display the same.

With these and other objects in view, as will appear as the description proceeds, the invention consists in the novel features of construction, combinations of elements and arrangements of parts hereinafter to be fully described and pointed out in the appended claim.

In the accompanying drawing:

Figure 1 is a front elevation of the improved sample display holder comprising the present invention,

Figure 2 is a top plan view thereof,

Figure 3 is a vertical transverse section taken on the line 3—3 of Figure 1,

Figure 4 is a vertical longitudinal sectional view taken on the line 4—4 of Figure 2.

Referring more particularly to the drawing the improved sample holder is designated in its entirety by the letter A. This holder is found to comprise a supporting frame, which consists of a base plate 1, adapted to rest flatly upon a suitable supporting surface and

of sufficient width to possess the desired degree of stability so as to prevent the holder from tipping laterally.

Arising centrally and longitudinally from the plate 1 is a vertical wall 2, which is of inverted U shaped formation and includes a longitudinally extending body portion 3 and spaced depending sides 4. The upper surface of the base plate 1 is suitably socketed for the reception of tenons 5 provided upon the lower edges of the sides 4 and by this construction a firm connection is provided between the plate 1 and the wall 2. In addition, however, wood screws 6 pass upwardly through the plate 1 and are threaded into the lower end of the sides 4. These screws are, however, normally concealed from view and are accessible only by inverting the normal position of the holder.

In addition, the upper surface of the plate 1 is provided with a plurality of pockets 7 of a diameter sufficient to receive the lower portion of a plurality of glass jars 8, in which are retained various merchandised articles or bodies adapted for display. In this instance the jars are of such construction as to display admirably such materials as sand, gravel and finely crushed stone, although it will be understood that the invention is in no manner limited to the display of these particular materials, but may be employed wherever it is found desirable in such capacities for example as the display of various grades of motor lubricating oils.

In order to prevent removal of the jars from the holder, the lower edge of the body portion 3 of the wall 2 has secured thereto a horizontally disposed, longitudinally extending retaining bar 9, which has its under surface socketed as at 10 for the reception of the removable tops 11 of the jars 8.

It will be understood that when the jars 8 are positioned in the pockets 7 and have their tops 11 positioned in the recesses 10, and the wall 2 then tightly secured to the base plate 1, it will be normally impossible to remove the jars from the holder or to remove the sample from the individual jars. Where the jars are readily removable it has been found that the contents thereof are frequently taken

out, lost or misplaced, so that confusion and difficulty is encountered in maintaining the various samples in their proper individual order. These difficulties are overcome in the present invention in that in order to remove the jars it is necessary to disconnect the wall 2 from the base plate 1, and since this involves the removal of the screws 6 it has been found that the samples are preserved and maintained in their original condition.

10 While the jars are locked in position within the frame, never-the-less, nothing has been done to the holder which in any way obstructs a clear and comprehensive view of the individual jars, so that careful examinations may be made of the individual samples without necessitating their removal from the holder. The front surface of the body portion 3 may be provided with a plurality of card frames 12 by which the different jars and their contents may be readily identified.

15 Also, the rear surface of the body portion 3, in connection with the bar 9, may be formed with pockets or holders 13 adapted for the accommodation of leaflets, booklets or other advertising matter employed in connection with the display of the samples.

20

What is claimed is:

25 A sample display holder, comprising a frame formed to include a base plate having a plurality of pockets provided in the upper surface thereof and adapted to receive a plurality of glass jars, a vertically disposed retaining wall having a slot formed therein for the reception of said jars, a bar carried by said wall and having the under surface thereof pocketed for the reception of the upper end of said jars, and fastening devices connecting said wall with said base plate whereby the jars will be rigidly held within said holder.
